Des. 1137

Francis McStrong & Thomas Ross of Brandon, Vt.
Letters Patent No 1137 Dated Aug. 23. 1859.

The schedule referred to in these Letters Patent and making part of the same.

To all whom it may concern:

Be it known that We Francis M. Strong & Thomas Rast, both of Brandon, in the County of Rutland and State of Vermont, have invented or produced a new and original design for the Cases of what are generally known as Union Scales, and We do hereby declare that the following is a full clear and exact description of the same, reference being had to the annexed drawings making a part of this specification, in which-

Figure 1. is a side elevation of the scale Case of our design.

Figure 2. a plan or top view of ditto.

Figure 3. a longitudinal vertical and central section of ditto.

Similar letters of reference indicate corresponding parts in the several figures.

The Union Scales are a combination of the platform and center scales and hence their name,

A represents a circular case which encompasses the lenses of the largest platform. This case is of the form of two Cymas a, b, the upper one a, being a cyma recta and the lower one b, a cyma reversa. The two Cymas are connected by a small bead or moulding c, and a slightly projecting moulding d, is at the base of the case A.

B, is a circular case which in connection with a hollow case C, and cap D, encompasses the lenses or Mechanism of the smaller platform.

The case B, is also formed of two Cymas e, f, precisely the same as the case A, the cyma e, being the cyma recta and f, the cyma reversa connected by a bead g. The cap D, is of the form of a cyma recta having a small ogee bead h, at its base. The two cases A, B, are connected by a shell E, the sides i, l, of which are of serpentine form as shown clearly in figure 2. - the top j, of the shell being transversely convex.

The moulding d, at the base of case A, extends entirely around the whole case.

Having thus described our invention what we claim as new and desire to secure by Letters Patent is,

The configuration of the parts herein shown and described to form a new and original design for the Cases of what are known as the Union Scales.
